TOOTH POWDER DISPENSER

Ferdinand L. Reuter, Wausau, Wis.

Application April 25, 1941, Serial No. 390,396

1 Claim. (Cl. 221—65)

This invention relates to new and useful improvements in tooth powder containers and more particularly to means for accurately dispensing tooth powder onto tooth brushes without wasting the powder.

The principal object of the present invention is to provide a closure for tooth powder boxes constructed in such a manner as to receive the head of a tooth brush and accurately position the same in such a manner that when the tooth powder box is inverted the tooth powder will be dispensed onto the bristles of the brush in a uniform and accurate manner.

Other objects and advantages of the invention will become apparent to the reader of the following description.

In the drawings—

Figure 1 is a front elevational view.

Figure 2 is a fragmentary side elevational view.

Figure 3 is a fragmentary vertical sectional view showing the gate in closed position.

Figure 4 is a vertical sectional view showing powder returning to the powder can.

Figure 5 is a fragmentary detail sectional view showing powder being dispensed onto the bristles of a brush.

Figure 6 is a side elevational view of the attachment.

Figure 7 is a bottom plan view of the attachment.

Figure 8 is a plan view of the gate.

Referring to the drawings wherein like numerals designate like parts, it can be seen that numeral 5 denotes a powder can having a cylindrical neck 6.

The present invention is generally referred to by numeral 7 and consists of a cap 8 and a box-like structure 9 connected to said cap 8 by a tapered neck portion 10. As shown in Figure 3 one end of this box 9 has an opening 11 therein which is just sufficiently large to permit the entrance of a tooth brush head, as suggested in Figure 5. Just under the box 9, the front wall

of the neck 10 has a sight opening 12 therein through which the flow of tooth powder 13 can be seen when the can 5 is inverted as shown in Figure 5. For guiding the powder and closing off the can 5, when the can is not in use, a flap or gate 14 is mounted on a transverse member 15 in the neck 10 and at a point directly above the sloping front wall of the neck, to the end that when the gate gravitates to a normal position when the can 5 is in an upright position, the lower edge of the gate will assume the position shown in Figure 3, against the lower portion of the sloping wall and, of course, the cap 8 can be rotated on the neck 6 to move the opening 16 out of registry with the opening 17.

Any excess powder which did not remain on the bristles when the parts were in the position shown in Figure 5, will return to the can 5 behind the gate, following the path suggested in Figure 4.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

A tooth powder dispenser comprising a container having a neck on its upper portion provided with an opening, a cap on the neck of the container, a box structure, a second neck rising eccentrically from the cap and connecting the box structure with the cap, said cap also having an opening registering with the opening of the first neck, said second neck having a sight opening therein and one end of the box structure having a tooth brush entrance opening therein, and a powder guiding gate in the second neck portion deflecting powder from the sight opening, said cap being rotatable on the first neck to move the openings in the second neck and cap into and out of registration.

FERDINAND L. REUTER.
